RECORD-CONTROLLED MACHINE

Ralph E. Page, West Orange, N. J., assignor to
 International Business Machines Corporation,
 New York, N. Y., a corporation of New York

Application March 25, 1938, Serial No. 198,018

5 Claims. (Cl. 74—393)

This invention relates to record-controlled machines particularly those controlled by perforating accounting and statistical record cards such as are used in the well known Hollerith system.

5 The broad object of the present invention is to provide an improved driving mechanism for record-controlled machines.

An object is to provide an improved driving mechanism for machines which require the use 10 of one-revolution clutches which must be started from rest repeatedly in the course of the operation of the machine.

An object is to provide a driving mechanism which causes the speed of the shaft which drives 15 certain parts controlled by clutches to be reduced at the point where the clutches are engaged without actually stopping the driving shaft, in order to permit the clutches to be engaged without risk of rebound of the driven parts and avoid 20 other difficulties which are experienced when mechanisms must be started suddenly from rest by a drive shaft which is rotating continually.

An object is to provide a driving mechanism for machines of the above type which results in 25 smoother operation and closer synchronization of parts which must be started and stopped and synchronized by means of clutches.

Further objects of the instant invention reside in any novel feature of construction or 30 operation or novel combination of parts present in the embodiment of the invention described and shown in the accompanying drawings, whether within or without the scope of the appended claims and irrespective of other specific 35 statements as to the scope of the invention contained herein.

In the drawings:

Fig. 1 is a plan view of a portion of the left hand end of the machine and shows the driving 40 mechanism;

Fig. 2 is a front elevation of the driving mechanism;

Fig. 3 is a left side view partly in section of the driving mechanism;

Fig. 4 is a curve showing how the speed of the driven shaft varies in a single revolution thereof.

The drawings show how the driving mechanism is incorporated in a record-controlled machine and by way of example the one disclosed in 50 application Serial No. 117,493, filed December 24, 1936, by Ralph E. Page, has been selected. It will be evident from the following description that the invention disclosed herein may be applied to other machines equally as well; therefore, it is not desired to limit the application of 55

the invention to the machine selected for purposes of description.

The main framework of the machine includes an end plate 10 and a back plate 11 which is secured to the rear edge of the end plate 10 by 5 means of screws. Bars like 12 are secured to the back of plate 11 in spaced relation with said plate by means of studs 13 (Fig. 1) which are screwed into tapped holes in the rear edge of plate 10, the studs 13 also serving to secure 10 the plate 11 to plate 10. The bar 12 supports the comparing units described in the above application, one of which is generally designated 14 in Figs. 1 and 3. Secured to the left hand face of the frame plate 10 is a frame casting 15 15 on which is mounted the driving mechanism.

The machine is driven by means of a motor, not shown, through a belt 16 and a pulley 17 which is rotatably mounted on a stud 18 supported by a boss 15a formed in the casting 15, 20 the pulley 17 rotating in the direction of the arrow in Fig. 3. Secured to the pulley 17 is a pinion 19 which meshes with a large gear 20 rotatably mounted upon the main drive shaft of the machine which is designated 21 in the drawings. The motor constantly rotates the pulley 17 while the machine is in use, whereby the gear 20 will be constantly rotated in a counterclockwise direction (Fig. 3).

The left hand end of shaft 21 is supported by 30 a pair of anti-friction bearings 22 mounted in a block 23 which is secured to frame casting 15 by means of screws 24. The block 23 is substantially cylindrical but is flattened where it is in contact with the frame 15, said frame being 35 formed with a lug 15b extending at right angles to the plane of the plate 10 for mounting said block.

Means are provided to interconnect the gear 20 and the shaft 21 whereby the shaft is caused 40 to oscillate periodically with reference to the gear, so that the speed of the shaft varies periodically while the gear 20 is being rotated at a constant speed. Pivoted on a stud 25 carried by the gear 20 is a lever 26 which takes the form 45 of an open frame having two branches connected at diametrically opposite points of shaft 21 near the periphery of the gear 20. Secured to the shaft 21 adjacent lever 26 is an arm 27 which is mounted on said shaft by means of a 50 hub pinned to the shaft, whereby the arm rotates therewith. The bulk of arm 27 is in the plane of the lever 26 within the space formed by the two interconnected branches comprising said lever. The arm 27 is also bent to the right 55

and outwardly at right angles to the shaft 21 (Fig. 1) at which point it is bifurcated.

Pivotedly mounted upon a stud 28 carried by lever 26 is a block 29 which has two oppositely disposed shoulders on which the parallel side walls of the bifurcation in arm 27 rests with a sliding fit. A washer which is larger in diameter than the width of the bifurcation in arm 27 and a retaining clip of conventional form forced 10 into a circumferential groove on the end of the stud 28 loosely holds the walls of the bifurcations in arm 27 in engagement with the shoulders on the block 28 whereby lever 26 is capable of oscillatory motion with respect to gear 20 and 15 the pivot 28 has a slight radial movement relative to the shaft 21. A cam roller 30 is mounted upon a stud 31 carried by one of the branches of lever 26 and rides in a cam slot 23a but in the left hand face (Fig. 1) of the block 23.

20 As the gear 20 rotates the stud 25 forces the lever 26 to rotate in a counterclockwise direction and thereby, through the stud 28 and block 29, produces similar motion in the arm 27 due to the fact that the pin 31 carrying the cam roller 25 acts as a fulcrum for the lever 26. As the gear 20 rotates, the stud 31 is caused to travel in a counterclockwise direction whereby the roller 30 follows the cam slot 23a. If the entire cam slot 23a is made concentric with the shaft 30 21, the gear 20 will be in effect locked to the shaft 21 and both will rotate at the same speed, as the pins 28, 31, and 25 will all follow concentric circular paths.

The cam slot 23a is circular with respect to the shaft 21 for approximately 192° and between this point and 360° the cam groove turns inwardly toward the center of shaft 21 for a brief dwell period at 276° and then outwardly to again meet the concentric portion at 360°. Thus, in 35 effect the cam has first a drop and then a rise of approximately 84° each. In Fig. 3 the roller 30 is shown in the brief dwell which occurs after 276° of rotation of the shaft from an arbitrary starting position, it being remembered that the shaft rotates continuously. This arbitrary starting position may be considered to be the point at which the roller 30 in Fig. 3 leaves the rise in the cam and re-enters the concentric portion of the groove.

40 During the initial period in which the roller 30 is traveling in the concentric portion of the cam groove, the studs 25, 28, and 31 all follow in circular paths which are all concentric with shaft 21 and the arm 27 is not displaced relative 45 to the driving gear 20. After 192° of rotation from the arbitrary starting point the roller 31 reaches the drop in the cam groove and commences to move inwardly toward the shaft 21. Owing to the shape of the cam groove, the 50 initial inward radial movement of the roller 31 is rather slow but, as the roller approaches the half way point between the dwell and the end of the concentric portion of the cam groove, the speed of roller toward the shaft 21 reaches 55 a maximum and then starts to move more slowly until the inward movement becomes zero when the roller reaches the brief dwell in the cam groove. During the inward movement of the roller, the gear 20 maintains its constant speed 60 whereby the lever 26 is caused to rock in a clockwise direction on the stud 25 in consequence of the movement of roller 30 toward the shaft 21. Thus, the arm 27 is caused to move in a clockwise direction relative to gear 20 and this 65 movement, which is slow at first but is continually 70

increasing until the half way point is reached, causes the arm 27 to lag behind the gear 20. In other words, from 192° of rotation to 234° of rotation, which corresponds with the half way point, the shaft 21 loses speed. The minimum 5 speed is reached at 234° after which the roller 30 in its continued movement toward the shaft 21 moves with diminishing speed radially until, when the roller reaches the dwell which occurs at 276° of rotation of the gear 20, the roller remains stationary momentarily whereby the arm 27 is held fixed relative to gear 20 and both the gear and shaft 21 travel at the same speed as indicated by the curve in Fig. 4.

During the next 84° of rotation of gear 20, 15 the roller 30 travels up the rise in the cam groove 23a causing the speed of shaft 21 to increase, slowly at first, and reaching a maximum at 318° which occurs when the roller is approximately half way up the rise. Thereafter, the 20 roller 30 continues its outward movement away from shaft 21 at a continually diminishing speed until the radial speed of the roller becomes zero, when it again enters the concentric portion of the cam groove. The shape of the cam and the 25 relation of the parts controlled by the cam groove is such that at 234° the shaft 21 is momentarily turning at approximately 40% of its normal speed in illustrative embodiment of the invention and at 318° at 40% above normal. 30 However, it will be understood that by alteration in the duration of the dwell periods and by changing the shape or extent of the drop and rise in the cam groove the speed may be varied between wide limits and the periods of reduced or increased speed changed as desired. It is not desired, therefore, to be limited either by the shape of the parts or by the specific form of cam groove 35 illustrated in the drawings.

It will be seen from the foregoing that, while 40 the gear 20 rotates at a constant speed, the speed of shaft 21 oscillates between maximum and minimum limits, the minimum limit being attained after 234° of rotation from the end of the rise and the maximum being attained after 45 approximately 318° of rotation from the end of the rise.

The shaft 21 not only drives the comparing unit 14 through spur gears 32 but also drives the pocket feed rollers 33 (Figs. 1 and 2) by 50 means of spiral pinions 34. Said shaft through clutches and driven shafts not shown, which clutches are of the one-revolution type having a definite point of engagement, also drives certain other feed rollers not shown and other mechanisms of the machine. Since these clutches are of the one-revolution type, it has been found by experience that during the operation of the machine described in the above application, the clutches engage with a jar and, since they drive 60 two independent card feed mechanisms which must be kept in exact synchronism, difficulty has been experienced with the machine getting out of time due to the fact that the driven shafts tend to rebound unequally when the clutches 65 engage. With the drive mechanism shown in the drawings, the machine is so timed that the energization of the magnets which control the clutches takes place slightly before 234° point in the cycle, whereby at the point of engagement with the clutches, the main drive shaft 21 will be turning at its minimum speed thereby causing the engagement of the clutches to be accomplished 70 without any of the harmful effects experienced 75

with the machine described in the above application.

5 In the comparing unit 14 and in the other similar comparing unit which is not shown but which is described in the above application, there is provided certain bail mechanism which is caused to oscillate back and forth by means of a cam and drives certain parts which take numerical settings under control of the perforated records which control the operation of the machine. Since the timing of the bail mechanisms is such that they commence their operating stroke shortly before the feed clutch is engaged, it is evident that these bails will operate more smoothly than heretofore because at the time the bails are changing their direction of movement from the restoring movement to their active stroke, the speed of shaft 21 will be considerably less than the speed of gear 20.

20 While there has been shown and described and pointed out the fundamental novel features of the invention as applied to a single modification, it will be understood that various omissions and substitutions and changes in the form and 25 details of the device illustrated and in its operation may be made by those skilled in the art without departing from the spirit of the invention. It is the intention therefore to be limited only as indicated by the scope of the following 30 claims.

What is claimed is:

1. In driving mechanism for record controlled machines, a continually rotating driving member, a driven member, an arm connected to the driven member, a lever having its ends pivotally connected to said arm and said driving member, a roller on said lever intermediate its ends and a relatively fixed cam controlling said roller, said roller following the contour of said cam as the 40 driving and driven members are rotated, said cam being so shaped that during a portion of the revolution of the driving member the end of said lever connected to said arm is displaced and effects a displacement of said arm to an extent 45 determined by the shape of the cam whereby to cause said arm and the driven member to first lag in speed behind the driving member, and thereafter to recover the loss in speed.

2. In a machine of the class described, the 50 combination of a driving gear, a driven shaft, an arm secured to said shaft, a lever having its ends pivotally connected to said arm and said

gear, a fixed cam mounted adjacent said lever and a roller mounted on said lever intermediate its ends and engaging said cam whereby when the gear rotates said roller is caused to follow the contour of the fixed cam, said cam being so shaped that the driven shaft is caused to lag and lead respectively in speed relative to the gear.

3. In a machine of the class described, the combination of a continually rotating driving element, a driven element mounted in juxtaposition to the driving element, a lever pivotally connected at its ends to the driving and driven elements respectively, and cam means acting upon said lever intermediate its ends for producing a periodic displacement of said lever relative to the driving element during the course of the rotation of the driving element whereby to vary the speed of the driven element periodically.

4. In a machine of the class described, the combination of rotatable driving and driven elements, a lever pivotally connected at its ends to the driving and driven elements respectively, and cam means acting upon said lever near its center and operative during the course of the rotation of the driving element to cause a periodic oscillation of said lever about its pivotal connection to said driving element whereby to vary the speed of the driven element.

5. In a machine of the class described, the combination of a rotatable driving element, a 30 rotatable driven element mounted adjacent the driving element, said driving and driven elements having their axes of rotation coincidental, a rigid coupling lever extending substantially diametrical of both the driving and driven members and 35 pivotally interconnecting the driving and driven members at diametrically opposite points, a cam mounted adjacent the driving and driven members so as to be coaxial therewith and having a cam track disposed eccentric with the axis of 40 rotation of the driving and driven members, and a cam follower located intermediate the ends of said member close to its axis of rotation and cooperating with said cam track, said cam track causing said member to be oscillated about its 45 pivot to the driving member as a center so as to periodically advance and retard the driven member during the course of its rotation whereby to periodically vary the speed of the driven member.

50 RALPH E. PAGE.
